(57) **CLAIM**

I claim the ornamental design for a neck sun drape for hard hats, as shown and described.

DESCRIPTION

FIG. 1 is a rear perspective view of a neck sun drape for hard hats showing my new design;

FIG. 2 is a top perspective view thereof;

FIG. 3 is a top plan view thereof;

FIG. 4 is a bottom plan view thereof;

FIG. 5 is a side elevation view thereof;

FIG. 6 is a side elevation view of the opposite side of FIG. 5;

FIG. 7 is an end elevation view thereof;

FIG. 8 is a rear perspective view of a second embodiment thereof;

FIG. 9 is a top plan view of FIG. 8;

FIG. 10 is a bottom plan view of FIG. 8;

FIG. 11 is a side elevation view of FIG. 8;

FIG. 12 is a side elevation view of the opposite side of FIG. 11; and,

FIG. 13 is an end elevation view of FIG. 8.

The helmet and hook and loop fastener shown in broken lines form no part of the claimed design. All other broken lines represent conventional stitching. The crosshatch surface shading is understood to repeat throughout the indicated area.
